UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed March 26, 1924. Serial No. 701,913.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to machines for 10 typing upon multiple-ply webs as disclosed in the patent to Wernery & Smith, No. 1,132,055, granted March 16, 1915, in which a web composed of several plies may have successive forms or bills printed thereon, 15 said plies being interleaved with carbon-sheets and fed around a cylindrical platen, the platen being swung up to release the web, to facilitate shifting of the carbon-sheets to a fresh portion of the web.

20 More particularly, the invention relates to tally-strip or record-sheet feeding mechanism to be used in such machines. In my co-pending application No. 696,556, filed March 3, 1924, provision is made to line-space a tally-sheet once for each bill-length, 25 so that the names or items appearing on the successive bills may be copied in condensed form on the tally-sheet.

An object of the present invention is to 30 line-space the tally-sheet for each line-spacing operation of the bill-sheet, so that all of the items typed on the bill are copied on the tally-sheet. Preferably these items are copied in condensed form on the tally-sheet. 35 For example, the items copied on the tally-sheet may be arranged at single line-space intervals, while the items on the bill-sheet may be arranged at two or three line-space intervals.

40 A take-up roll or receiving roll is provided to feed the tally-sheet, the leading end of which is connected to said take-up roll. Said take-up roll is connected with the platen line-spacing mechanism to enable the 45 tally-sheet and the bill-sheet to be line-spaced simultaneously by the actuation of the regular line-space handle. To this end the platen line-spacing mechanism comprises the usual line-space slide which is supported 50 on the platen-frame, and the tally-strip line-spacing mechanism comprises a line-space slide which may be supported on the carriage-frame, and there is secured to one of said slides an arm extending to the other

slide, to connect said slides, so that said 55 slides may be operated simultaneously. Since the platen line-spacing mechanism is carried by the platen-frame and the tally-sheet line-spacing means is supported on the carriage-frame, provision is herein made by 60 means of a slot in said connecting arm to enable the platen line-spacing mechanism to be freely shifted relatively to the tally-sheet line-spacing mechanism during case-shifting movements of said platen. 65

A feature of the invention relates to the connection from the platen line-spacing mechanism to the take-up roll for the tally-sheet, which is constructed to enable the swing-frame to be freely operated to swing 70 the platen in order to facilitate the shifting of the carbon-sheets. To this end, the take-up roll has secured thereto a ratchet-wheel which forms part of its line-spacing mechanism, and which may be swung away from 75 a relatively-fixed co-operating pawl when the platen is so actuated.

Another feature of the invention resides in the provision of a carbon-sheet for the 80 tally-sheet or strip, which may be connected to the regular carbon-carrier of the continuous billing machine, so that it may be retracted with the carbon-sheets interleaved between the plies of the bill-web.

In order to condense the items copied on 85 the tally-sheet, the tally-sheet is usually fed slower than the bill-sheet, and it is common practice to feed the tally carbon-sheet at the same speed as the tally-sheet. If the tally carbon-sheet were fed at the same speed as 90 the tally-sheet in the present machine, however, in which the tally-sheet also moves at a slower speed than the bill-web, and in which, it will be remembered, the tally carbon-sheet is connected to the carbon-carrier, 95 which travels at a faster speed than that of the tally-sheet, the tally carbon-sheet would buckle or pile up behind the platen, because its rear end would be advanced faster by the carbon-carrier than its forward end is advanced by means of the take-up roll. Another feature of the invention is to prevent 100 buckling of the tally carbon-sheet. To this end it is fed faster than the tally-sheet, preferably at the same speed as the bill-web, 105 and consequently at the same speed as the carbon-carrier to which it is connected. For this purpose, the tally carbon-sheet is made

wider than the bill-sheet to extend beyond the side edge of the latter, so that the tally carbon-sheet may be acted upon by the usual feed-rolls which advance it around the platen with the bill-web.

- In the present machine the tally-sheet is nearest the platen, and consequently there may exist, at times, a tendency to draw said tally-sheet around the platen by means of the bill-web due to the friction of the bill-web against the tally-sheet, thus causing the tally-sheet to be advanced faster than is desired. A further feature of the invention relates to means to overcome this tendency.
- 15 To this end there is provided a friction device, which is preferably located behind the platen and is effective to engage the tally-sheet, to thus prevent said tally-sheet from being accidentally advanced at an undesired speed.

Other features and advantages will hereinafter appear.

In the accompanying drawings,

Figure 1 is a side elevation, showing the carriage of a continuous billing typewriting machine, with my invention applied thereto.

Figure 2 is a fragmentary top plan view of the parts shown in Figure 1.

Figure 3 is a diagrammatic side view, showing the parts in position when the platen is swung up to release the work-web to facilitate the shifting of the carbon-sheets.

Figure 4 is a diagrammatic front view, showing the arrangement of bill-web, tally sheet and the carbon-sheets with relation to each other, and also with relation to the feed-rollers.

Figure 5 is a view similar to Figure 4, but shows another arrangement of the tally sheet with relation to the work-web and the feed-rollers.

The invention is shown applied to an Underwood continuous billing machine in which type-bars 10, when operated by keys 45 (not shown), swing upwardly and rearwardly to print against the front of a cylindrical platen 11. The platen is mounted in a platen-shift-frame 12, which is supported in a carriage-frame 13 for case-shifting movements, to enable the platen to be brought into co-operative relation with lower-case types 14 or upper-case types 15 on the type-bars.

55 A web-supporting table 16 extends rearwardly from the platen, over which a composite work-web 17 may be advanced from any suitable source of supply to the platen to be typed upon, said composite web being composed of separate plies 18 with carbon-sheets 19 interleaved between them, and which may be fed around said platen by feed-rolls 21 bearing against the under side thereof. The table 16 is connected to the carriage-frame 13 in the usual way by brackets 20 secured to said carriage-frame

to travel with the carriage during letter-spacing movements thereof, said table being guided in the usual way, as shown in the Wernery & Smith patent above referred to. The carbon-sheets are attached, at their rear ends, to individual bars 22^a on a carbon-carrier 22, which is mounted on the web supporting table 16 in a manner to be moved back and forth on said table, or, in other words, towards the platen, with the carbon-sheets 19 while the composite web is fed around the platen and away from the platen in order to shift the carbon-sheets to a fresh portion of the composite web. The composite web may be provided with regular forms or bills of equal length printed thereon, as is well understood in the art, and after a bill or set of superposed bills has been completed, the carbon-sheets 19 are retracted or shifted to a succeeding set of bills by means of the carbon-carrier, which is actuated by a handle 23 and arrested by an adjustable stop 24. The bill-web 17 is then pulled forward against a gage 25 on a gage-bar 26 to position the typed set of bills prior to severing them from the web.

To facilitate the shifting of the carbon-sheets and the gaging of the typed bills, the platen may be swung up to an abnormal position, shown in Figure 3, to enable the web to be straightened out, so that the carbon-sheets may be readily shifted relatively thereto. For this purpose, the platen is supported in a swing frame 27, Figure 1, pivotally mounted at 28 in the platen-frame 12, in a manner similar to that disclosed in the application of William F. Helmond, Serial No. 609,560, filed December 29, 1922.

The platen line-spacing mechanism may include a line-space wheel 29^a, which may be connected to the platen, as in said Helmond application, to enable the swinging movement of said platen. The line-space wheel is operated by a spring-pressed pawl 29 pivotally supported on a line-space slide 30 suitably supported on the platen-frame 12, said slide being actuatable by the usual line-space handle (not shown) against the tension of a return spring 31.

A record-sheet or tally-sheet 32 is provided, upon which the items typed on the various bills are copied. The record-sheet is fed from any suitable source of supply, which may be located at the back of the machine, and is conducted over the web-table 16 and the carbon-carrier thereon, and then downwardly at the front of said table with the bill-web 17 towards and around said platen, and upwardly at the front of said platen past the printing point.

It is desirable to have the items copied on the tally-sheet in condensed form. Consequently there is provided means which may comprise a separate line-spacing mechanism for said tally-sheet, so that it may

be fed slower than the bill-web. To this end, the leading edge of the tally-sheet 32 is secured to a take-up roll 33 fixed to a shaft 34 revolubly supported in brackets 35 secured to the platen-swing-frame 27. The shaft is provided at one end with a ratchet-wheel 36 to be actuated to revolve the shaft, and consequently the roll 33 thereon, in a clockwise direction by a spring-pressed pawl 37 supported on a slide 38, which may be reciprocated in a bracket 39 secured to one of the table-supporting brackets 20.

Connection between the tally-sheet line-spacing slide 38 and the platen line-spacing slide 30 is made so that they may be operated simultaneously by the actuation of the usual line-spacing handle (not shown), which engages the platen line-space slide 30. Said connection may comprise an extension or arm 40, which is herein shown secured to the platen line-space slide 30, and which extends upwardly to the record-sheet line-space slide 38. Said arm has at its upper end a slot 41 to receive a lateral extension 42 on said slide 38 to connect it with said slide. It will be noted that the platen line-spacing mechanism is supported on the platen-frame, which, it will be remembered, is shiftable from lower-case position to upper-case position, and that the line-space slide 38 for the tally-sheet is supported on the carriage-frame 13, which is relatively fixed. Consequently provision is made by extending the slot 41 downwardly in said arm 40, to enable the arm to be shifted with the platen relatively to the line-space slide 38 which it operates.

The platen line-space slide 30 always moves through the same linear distance, as in the Underwood machine, irrespective of the number of line-spaces imparted to the platen by each operation of said slide, the line-spacing mechanism being settable by a line-space control-lever 43, to enable the platen to be line-spaced one, two or three line-space distances at each actuation of the line-space slide, according to the setting of said control lever. Said control lever 45 is connected to a pawl-controlling element 44 having a shelf 45 thereon over which an extension 46 of the line-space pawl rides, to enable the line-space pawl to engage the line-space wheel 29 sooner or later, according to the magnitude of the line-space movement of the platen. The record-sheet 32, however, is always fed substantially a single line-space distance. To this end, the line-space slide 38, to which is connected the line-space pawl 37, moves idly a considerable distance, and actuates the ratchet-wheel 36 through the medium of said pawl 37 during the latter part of its movement. It will be understood that the upper end of the arm 40 is to one side of the bracket 39

(Figure 2), so that not to be obstructed in its movement by said bracket.

It will be understood that the relation between the line-space wheel 36, associated with the take-up roll 33, and its co-operating line-space pawl 37, is such that said line-space wheel may readily be swung away from the pawl during a platen-swinging operation, and when the platen is again lowered to its typing position that the line-space wheel is brought back by the swing-frame into effective relation with the line-space pawl.

A carbon-sheet 47 is provided for the tally-sheet, said carbon-sheet being connected at its rear end to a carbon-blade 48 supported on the carbon-carrier 22, so that said carbon-sheet may be retracted, with the other carbon-sheets 19, to a fresh portion of the tally-sheet at each carbon-displacing operation. Since the tally carbon-sheet 47 is connected with the carbon-carrier 22, which moves at the same speed as the bill-web 17 and faster than the tally-sheet 32, it is desirable to feed the tally carbon-sheet at the same speed as the bill-web, and faster than the tally-sheet, to prevent buckling of said tally carbon-sheet 47, which would ordinarily occur, in the present machine, if the tally carbon-sheet were fed at the same speed as the tally-sheet 32.

To enable the tally carbon-sheet 47 to be fed with the bill-web 17, it extends considerably beyond the right-hand edge of the tally-sheet 32 (Figure 4), so that it may be fed by means of the feed-rolls 21, which are located to one side of the tally-sheet 32, so that the latter may be fed independently of the bill-web. The tally-sheet may be located in the middle of the bill-web, as shown in Figure 5, instead of the left-hand end thereof, as shown in Figure 4, and in which case the feed-rolls 21 are arranged one near each side of the bill-web 17 and beyond the sides of the tally-sheet 32.

Since the tally-sheet is nearest the platen, there may be sufficient friction caused by the bill-web at times to tend to advance the tally-sheet at the same speed as the bill-web, which would be objectionable since it is desired to feed the tally-sheet at a slower speed in order to condense the typed items thereon. To overcome any such tendency, however, there is provided a friction device comprising a spring-pressed bar 50 co-operating with a bar 51 secured to the web-supporting table 16 by screws 52, the tally-sheet passing between said bars. It will be understood that this friction device will not interfere with the advancement of the tally-sheet around the platen since said tally-sheet is not frictionally driven through the medium of the feed-rolls 21, but is positively driven through the medium of the take-

up roll 33 to which, it will be remembered, the leading end of the record-sheet is attached.

When the platen is swung to its abnormal position to facilitate the displacing of the carbon-sheets, the tally-sheet bulges, as indicated at 53, but this bulge is again taken up when the platen is lowered to its typing position.

10 The work-web 17 may be fed relatively to the tally-sheet 32 through any desired number of line-space intervals, relatively to the tally-sheet 32, by means of a platen-rotating knob 54, which may be connected to rotate 15 the platen in the usual way, as described in the Wernery & Smith patent.

Variations may be resorted to within the scope of the invention, and portions of the improvements may be used without others.

20 Having thus described my invention, I claim:

1. In a typewriting machine, the combination of a platen around which a bill-sheet and a record-sheet may be fed, a swing-frame to lift said platen, line-spacing means for said platen to feed said bill-sheet, line-spacing mechanism comprising a line-space wheel on said swing-frame for the record-sheet, and a connection from the platen line-spacing means to the line-space wheel for the record-sheet, said connection being so arranged as to permit the line-space wheel to be swung with the swing-frame.

2. In a typewriting machine, the combination of a carriage, a platen around which a bill-sheet and a record-sheet may be fed, a swing-frame to lift said platen, line-spacing means for said platen to feed said bill-sheet, a receiving roll on said swing-frame for the record-sheet, line-spacing mechanism for said record-sheet, said line-spacing mechanism comprising a pawl on said carriage, and a line-space wheel carried by the swing-frame and connected to the receiving roll, and a connection between the platen line-spacing means and the pawl of the receiving roll line-spacing mechanism.

3. In a typewriting machine, the combination of a platen around which a bill-sheet and a record-sheet may be fed, a swing-frame to lift said platen, line-spacing mechanism for said platen to feed said bill-sheet, a receiving roll on said swing-frame for the record-sheet, a carriage-frame, a platen-frame supported in said carriage-frame for case-shifting movements, the swing-frame being supported by the platen-frame, line-spacing mechanism for said record-sheet, said line-spacing mechanism comprising means on the carriage-frame, said platen line-spacing mechanism being on said platen-frame, and a connection between the receiving roll line-spacing mechanism and the platen line-spacing mechanism to enable both line-spacing mechanisms to be

actuated simultaneously, the connection between said line-spacing mechanisms being so arranged as to enable the platen to be shifted to upper-case position with its line-spacing mechanism independently of the line-spacing mechanism of the receiving roll.

4. In a typewriting machine, the combination of a platen around which a bill-sheet and a record-sheet may be fed, a swing-frame to lift said platen, line-spacing mechanism for said platen to feed said bill-sheet, a receiving roll on said swing-frame for the record-sheet, a carriage-frame, a platen-frame supported in said carriage-frame for case-shifting movements, the swing-frame being supported by the platen-frame, line-spacing mechanism for said record-sheet, said line-spacing mechanism comprising a slide supported on the carriage-frame, platen line-spacing mechanism comprising a slide on the platen-frame, and a connection between the receiving roll line-spacing mechanism and the platen line-spacing mechanism to enable both line-spacing mechanisms to be actuated simultaneously, the connection between said line-spacing mechanisms comprising an arm secured to one of said slides and extending to the other slide, said arm having a slot in which the other slide engages to enable the platen to be shifted to upper-case position with its line-spacing mechanism independently of the line-spacing mechanism of the receiving roll.

5. In a typewriting machine, the combination of a platen, line-spacing mechanism for said platen to feed a work-sheet, a swing-frame supporting said platen which may be raised thereby to release the work-sheet, a take-up roll for a record-sheet on said swing-frame, and means actuated by said line-spacing mechanism to rotate said take-up roll to line-space the record-sheet, said means being arranged to permit the swing of the take-up roll with the platen.

6. In a typewriting machine, the combination of a platen around which a bill-sheet and a record-sheet may be fed, a swing-frame to lift said platen, line-spacing means for said platen to feed said bill-sheet, line-spacing mechanism comprising a line-spaced wheel on said swing-frame for the record-sheet, a connection from the platen line-spacing means to the line-space wheel for the record-sheet, said connection being arranged so as to permit the line-space wheel to be swung with the swing-frame, and means to enable the bill-sheet to be fed at a different speed than that of the record-sheet.

7. In a typewriting machine, the combination of a cylindrical platen, means to feed a record sheet about said platen, means to feed a bill-sheet with an interleaved carbon-sheet around said platen at a speed faster than that of the record-sheet, means bearing directly on the record-sheet to pre-

vent said sheet from being fed by the bill-sheet, means to release the bill-sheet and the carbon-sheet to enable the carbon-sheet to be retracted, and a device to retract 5 said carbon-sheet.

8. In a typewriting machine, the combination of a cylindrical platen, means to feed a tally-sheet about said platen, means comprising feed-rolls to advance a bill-sheet 10 with an interleaved carbon-sheet around said platen, the carbon-sheet being considerably wider than the tally-sheet, so that it presents a portion against which the feed-rolls may bear to advance it with the bill- 15 sheet, and means effective against the face of the tally-sheet to prevent said sheet from being fed around the platen by the bill-sheet.

9. In a typewriting machine, the combination of a cylindrical platen, means to 20 feed a tally-strip about said platen, means comprising feed-rolls to feed a work-sheet with an interleaved carbon-sheet around said platen, the carbon-sheet being considerably wider than the tally-strip, so that it presents a portion against which the feed-rolls 25 may bear to advance it with the work-sheet, means engaging the tally-strip to prevent a feeding movement thereof by the feeding of the carbon-sheet, means to release the 30 work-sheet and the carbon-sheet to enable the carbon-sheet to be retracted, and a device to retract said carbon-sheet.

10. In a typewriting machine, the combination of a cylindrical platen, means to 35 feed a record-sheet about said platen, means to feed a bill-sheet with an interleaved carbon-sheet around said platen at a speed faster than that of the record-sheet, means to release the bill-sheet and the carbon-sheet 40 to enable the carbon-sheet to be retracted, a device to retract said carbon-sheet, and friction means applied directly to both faces of the record-sheet to prevent a feeding movement thereof independently of the 45 record-sheet-feeding means.

11. The combination of a platen, means to feed a work-sheet around said platen, means to feed a tally-sheet at a slow speed around 50 said platen, and feed-restricting means behind the platen to engage both faces of the tally-sheet to prevent a feeding movement thereof independently of the tally-feeding means.

12. The combination of a platen, means 55 to feed a work-sheet around said platen, means to feed a tally-sheet at a speed slower than the work-sheet around said platen, and friction means behind the platen to engage the tally-sheet to promote said slow speed 60 of the tally-sheet, said friction means including a spring-pressed bar to bear against both faces of the tally-sheet.

13. In a typewriting machine, the combination of a carriage, a swing-frame on said carriage, a platen carried by said swing-frame, a roll to wind up a record-sheet thereon to feed it around said platen, said roll being supported on said frame, and platen-line-spacing mechanism to actuate 70 said roll to rotate the latter.

14. In a typewriting machine, the combination of a carriage, a swing-frame on said carriage, a platen carried by said swing-frame, a roll to wind up a record-sheet thereon to feed it around said platen, said 75 roll being supported on said frame, a ratchet wheel secured to said roll, a bracket on said carriage, a slide on said bracket, a pawl on said slide to engage said ratchet-wheel, platen-line-spacing mechanism, and a connection from the platen-line-spacing mechanism to said slide to actuate the latter to feed the record-sheet around said platen. 80

15. In a typewriting machine, the combination of a carriage, a swing-frame on 85 said carriage, a platen carried by said swing-frame, a roll to wind up a record-sheet thereon to feed it around said platen, said roll being supported on said frame, means to feed said sheet around said platen, and 90 means on said carriage to prevent accidental advancement of the sheet around said platen.

16. In a typewriting machine, the combination of a carriage, a swing-frame on 95 said carriage, a platen carried by said swing-frame, a roll to wind up a record-sheet thereon to feed it around said platen, said roll being supported on said frame, means to feed said sheet around said platen, and 100 means comprising a friction device on said carriage to prevent accidental advancement of the record-sheet around said platen.

17. In a typewriting machine, the combination of a carriage, a swing-frame on 105 said carriage, a platen carried by said swing-frame, a roll to wind up a record-sheet thereon to feed it around said platen, said roll being supported on said frame, a rearward extension connected to said carriage, 110 and a friction device secured to said extension, said friction device being effective to engage the record-sheet to prevent accidental advancement of said sheet.

18. In a typewriting machine, the combination of a platen, a work-sheet to be fed around the platen, a tally-sheet to underlie the work-sheet, a feed-resisting drag applied to both faces of the tally-sheet at the introductory side of the platen, and 115 means to differentially feed both sheets by a single line-spacing operation. 120
